(57) **CLAIM**

We claim the ornamental design for a door handle paddle, as shown and described.

DESCRIPTION

FIG. 1 is a perspective view of the first embodiment of the door handle paddle of the present invention.

FIG. 2 is a top plan view of the door handle paddle thereof, the undisclosed rear is not part of the claimed design;

FIG. 3 is an opposite side of the door handle paddle of FIG. 1;

FIG. 4 is an opposite side of the door handle paddle of FIG. 1;

FIG. 5 is an opposite end view of the door paddle of FIG. 1; FIG. 6 is an opposite end view of the door paddle of FIG. 1

FIG. 7 is a perspective view of the second embodiment of the door handle paddle of the present invention.

FIG. 8 is a top plan view of the door handle paddle shown in FIG. 7.

FIG. 9 is an opposite side view of the door paddle of FIG. 7;

FIG. 10 is an opposite side view of the door paddle of FIG. 7;

FIG. 11 is an opposite end view of the door paddle of FIG.

7; and,

FIG. 12 is an opposite end view of the door paddle of FIG.

7.

The broken lines are for illustrative purposes only and forms

no part of the claimed design.
